UNITED STATES PATENT OFFICE.

JACOB W. FENNEL, OF NEWBURGH, NEW YORK.

GAS AND AIR BURNING BURNER.

1,097,086.

Specification of Letters Patent.

Patented May 19, 1914.

Application filed February 20, 1914. Serial No. 819,977.

To all whom it may concern:

Be it known that I, JACOB W. FENNEL, a citizen of the United States, residing at Newburgh, in the county of Orange and State of New York, have invented certain new and useful Improvements in Gas and Air Burning Burners; and I do declare the following to be a full, clear, and exact description of the invention, such as will enable others skilled in the art to which it appertains to make and use the same.

This invention relates to improvements in air and gas mixers and more particularly to mixers of this character having gas and air burning burners.

The main object of the invention is to provide air supply means automatically controlled by the pressure of the inflowing gas.

Another object is to provide pressure controlled means for regulating the air supply to the mixing chamber so constructed as to be reliable and to enhance the life of said means.

Another object is to provide simple and efficient means for controlling the amount of gas admitted to the mixing chamber, said means being adjustable to vary the quantity of gas admitted.

Another object is to provide simple and effective adjusting means for the gas inlet.

With these and other objects in view, the invention consists of certain novel features of construction, and the combination and arrangements of parts as will be more fully described and claimed.

In the accompanying drawings: Figure 1 represents a side elevation of a burner equipped with this invention; Fig. 2 represents a longitudinal vertical section thereof; Fig. 3 represents an enlarged detail vertical section through the mixing chamber showing the gas check in side elevation; Fig. 4 is a transverse section taken on the line 4—4 of Fig. 2; Fig. 5 is a similar view taken on the line 5—5 of Fig. 2; Fig. 6 is a detail side elevation of the apertured cylindrical casing; Fig. 7 is a similar view taken from the opposite side.

In the embodiment illustrated the device is shown applied to an incandescent light burner, but it is to be understood that it may be used in connection with any form of gas burner to which it is adapted.

A gas supply pipe 1 is shown provided with the usual controlling cock 2 and having threaded thereon a nipple 3 which is pro-

vided at its upper end with a laterally extending base plate 4 herein shown circular and having a depending peripherally grooved flange 5 to which is secured a diaphragm 6 composed of leather or any other suitable material and having disks or plates 7 and 8 arranged on its opposite faces at the top thereof. The disk 7 is disposed inside said diaphragm and is preferably made larger than disk 8 which is arranged on the outside thereof, said inner disk having an annular depending flange 7' peripherally grooved to receive a clamping cord or wire 9 which secures the flexible body portion of the diaphragm to said disk as is shown clearly in Fig. 2.

A dome shaped hood or shell 10 incases the diaphragm 6 and is secured to the base plate 4 in any suitable manner and has an opening 11 in its top through which a rod 12 passes. This rod 12 is connected with the disk 8 and the upper end thereof beyond said shell 10 is forked, forming a yoke 13 the arms of which have inturned lateral fingers 13' for a purpose to be described. Coupled to the nipple 3 at one end is a curved by-pass pipe 14 the other end of which connects with an upwardly extending gas supply pipe 15. Mounted on this pipe 15 is an upwardly extending cylindrical member 16 closed at its lower end and open at its upper end and provided in its side walls near its lower end with a plurality of laterally spaced air inlet openings 17 of varying lengths. The top walls of these openings 17 are disposed in the same plane while the lower walls thereof are arranged in step-like relation as shown in Figs. 1, 6, and 7 whereby said openings gradually decrease in length and are adapted to be brought successively into operation for a purpose to be described. If desired, the walls of the casing 16 between the openings 17 may be perforated as shown at 18 in Figs. 1, 6 and 7 and said apertures coöperate with the openings 17 for admitting air to a mixing chamber to be described.

Depending from the burner B is a fluid feed or supply pipe 19 with which is detachably engaged a pipe 20 which merges at its lower end into an air and gas mixing chamber 21 which is formed by enlarging said pipe 20 intermediately of its ends. A cup like member 23 depends from the lower end of the mixing chamber 21 and has an opening in the bottom thereof through

which extends a pipe 24 which is connected with the pipe 15 being here shown detachably engaged therewith. On the upper end of the pipe 24 inside the mixing chamber 21 is a gas supply device 25 here shown of ovate form with its smaller end merging into the pipe 24, said pipe being provided with coarse threads which engage corresponding threads of the cup-shaped member 23 to adapt said device to be quickly adjusted when desired. Mounted on the pipe 20 is a shutter 26 here shown in the form of a tube telescopically engaged with the cylinder 16 fitting in said cylinder and spaced slightly from the side walls thereof a sufficient distance to permit it to move freely longitudinally therein without binding. This tubular shutter is provided at its upper end with a cap 27 which is slideable on the tube 20 and is held in yieldable engagement with the upper end of the mixing chamber by means of a coiled spring 28 which bears at one end on said cap and at its other end against a nut 29 threaded on the feed pipe 19 and which is adjustable to vary the tension of the spring and consequently the yielding movement of the shutter. This shutter is secured to the yoke 13, the fingers 13' of which are soldered or otherwise rigidly connected with its cap 27 at diametrically opposite points as is shown clearly in Fig. 2 and by means of which said shutter is moved vertically within the cylindrical casing 16 when the diaphragm 6 is expanded or collapsed, said shutter being controlled by the pressure of the gas under said diaphragm. The ovate member 25 is made hollow and is provided in its upper large end with slots 25' which extend at right angles to each other throughout the greater portion of the length of said member 25 and form expansible and compressible lobes 25a which are adapted to open and close for admitting more or less gas to the mixing chamber as may be desired, the opening of said lobes being controlled by the cup-shaped member 23 which is adapted to be screwed up or down on the stem or shank 24 of said member for forcing the lobes 25a formed between the slots toward each other when adjusted in one direction and which permits them to spread apart when adjusted in the opposite direction. This spreading of the lobes occurs owing to the fact that the member 25 is made of resilient material.

A channel bar 30 extends longitudinally of the shutter 26 on the inner face thereof with its groove opening inwardly and which is adapted to receive a finger 31 which projects laterally from the cup-shaped member 23 thus forming a connection between said member and the shutter, permitting the shutter to move longitudinally relative thereto without changing the position of said member 23, and when the shutter is

turned on the tube 20 which may be readily accomplished by grasping it between the fingers, the cup-shaped member 23 is correspondingly turned and is thereby adjusted relative to the ovate gas check 25 for regulating the amount of gas to be admitted through the slots 25' therein. 70

From the above description it will be obvious that the diaphragm 6 will be controlled by the gas pressure in the supply pipe 1 and through the rod 12 and yoke 13 control the position of the shutter 26 without necessitating any apertures being made in said diaphragm thereby prolonging the life thereof. 75

In the operation of the device when the burner B is to be lighted, the parts are in the position shown in Fig. 2, the diaphragm 6 being in collapsed position, it being understood that the check 25 has already been adjusted to permit the desired quantity of gas to be admitted therethrough. Immediately the cock 2 is opened the rich gas admitted will flow through pipes 1 and 14 and pass directly through pipes 15, shank 24, check 25 and pipe 20 into the burner without any air having been mixed therewith and when this rich gas is lighted, no explosion will occur such as usually takes place when mixed air and gas are ignited. The gas also flows through pipe 1 and nipple 3 under the diaphragm 6 and the pressure thereof causes said diaphragm to raise the rod 12 and the yoke 13 connected therewith, thereby elevating the shutter 26 and gradually opening the air inlet ports 17 in the cylinder 16 and permitting the air to flow into the mixing chamber and there combine with the gas which enters through the slots 25' in the check 25. As the diaphragm gradually expands the shutter continues to be raised gradually exposing the step-like lower ends of the openings 17 and thus admitting more air to the mixing chamber, the quantity admitted being controlled by the tension of the spring 28 which has been previously adjusted to admit a predetermined quantity of air proportionate to the amount of gas admitted through the check member 25. 100

I claim as my invention: 115

1. The combination with a gas burner, of a vibratory member controlled by the pressure of the gas supply, an air and gas mixing chamber having air inlet ports, a casing surrounding said chamber and having air inlet ports, a shutter telescopically engaged with said casing, means connecting said shutter with said vibratory member whereby said shutter is opened or closed according to the pressure of the gas supply, and means for regulating the quantity of gas admitted into said mixing chamber. 120

2. The combination with a gas burner, an air and gas mixing chamber connected therewith and having air inlet ports in its side 130

- walls, a gas supply pipe terminating in an egg-shaped member disposed in said mixing chamber and having discharge openings therein, means for adjusting said discharge openings to vary the amount of gas admitted to said chamber, and means for controlling the amount of air admitted to said chamber.
3. The combination with a gas burner, of a gas supply pipe having a diaphragm chamber communicating therewith, a by-pass pipe connected with said supply pipe, an air and gas mixing chamber connected with said burner, a gas supply member connected with said by-pass pipe and extending into said mixing chamber, said gas supply member having adjustable openings for varying the amount of gas admitted to said chamber, said chamber having air inlet ports, a shutter for controlling said air inlet ports connected with and controlled by said vibratory member, and means connected with said shutter for varying the size of the gas inlet openings.
4. The combination with a gas burner, of an air and gas mixing chamber, an egg-shaped gas supply member disposed in said chamber and having a screw threaded shank in threaded engagement with an opening in the bottom of said chamber and slotted to form expansible and compressible elements, and means for turning said chamber to control said expansible and compressible elements to vary the size of the gas outlet openings in said egg-shaped member.
5. The combination with a gas burner, of an air and gas mixing chamber, an egg-shaped gas supply member disposed in said chamber and having a screw threaded shank in threaded engagement with an opening in the bottom of said chamber and slotted to form expansible and compressible elements, and manually operated means for turning said chamber and thereby adjusting said expansible and compressible elements to vary the size of the gas outlet openings in said egg-shaped member.
6. The combination with a gas burner, of an air and gas mixing chamber provided with air inlets in its side walls, an egg-shaped gas supply member disposed in said chamber and having its small end extending downwardly and terminating in a threaded shank engaged with an opening in the bottom of said chamber and openings in its large end, a gas supply pipe connected with said shank, a vertically movable revolute shutter inclosing said mixing chamber and operable to control the air admitted thereto, and coöperating means on said shutter and chamber for turning the latter to adjust the size of the openings in said gas supply member.
7. The combination with a gas burner, of an air and gas mixing chamber provided with air inlets in its side walls, an egg-shaped gas supply member disposed in said chamber and having its small end extending downwardly and terminating in a threaded shank engaged with an opening in the bottom of said chamber and openings in its large end, a gas supply pipe connected with said shank, a vertically movable revolute shutter inclosing said mixing chamber, said shutter having a guide disposed longitudinally on its inner face and an element extending laterally from said mixing chamber and engaged with said guide whereby the turning of said shutter will operate to turn said chamber to adjust the size of the openings in said gas supply member.

In testimony whereof I have hereunto set my hand in presence of two subscribing witnesses.

JACOB W. FENNEL.
